UNITED STATES PATENT OFFICE.

LOUIS SCHULTZ, OF MILWAUKEE, WISCONSIN, ASSIGNOR TO THE SUNLITE COMPANY,
OF MILWAUKEE, WISCONSIN.

DESIGN FOR A CARDBOARD CARTON.

Application filed October 1, 1927. Serial No. 23,593. Term of patent 3½ years.

To all whom it may concern:

Be it known that I, LOUIS SCHULTZ, a citizen of the United States, and a resident of Milwaukee, in the county of Milwaukee and State of Wisconsin, have invented a new, original, and ornamental Design for a Cardboard Carton, of which the following is a specification, reference being had to the accompanying drawing, forming part thereof.

I claim:

The ornamental design for a cardboard carton, as shown.

In testimony that I claim the foregoing I have hereunto set my hand at Milwaukee, in the county of Milwaukee and State of Wisconsin.

LOUIS SCHULTZ.
